UNITED STATES PATENT OFFICE.

HOWARD P. SWINBURNE AND GEORGE S. CRAWFORD, OF GLASGOW, SCOTLAND.

TOOL-HOLDER.

1,148,202.

Specification of Letters Patent. Patented July 27, 1915.

Application filed November 25, 1912. Serial No. 733,517.

To all whom it may concern:

Be it known that we, HOWARD PERCY SWINBURNE and GEORGE SLOAN CRAWFORD, subjects of the King of Great Britain and 5 Ireland, and residents of Glasgow, Scotland, engineers, have invented new and useful Improvements in Tool-Holders, of which the following is a specification.

This invention has reference to and comprises improvements in chucks or like tool 10 holders for boring and drilling machines and the like and particularly relates to that type of chuck or tool holders which consist of a cylindrical and partly conical sleeve 15 within which are fitted paws or wedges (usually three in number) which are tightened or pressed on to the shank of a drill or other tool by the rotation of said sleeve.

In order that our said invention and the 20 manner of carrying the same into effect or practice may be properly understood, we have hereunto appended three sheets of explanatory drawings in which—

Figure 1 is a sectional elevation of our 25 improved chuck or tool holder for boring and drilling machines and the like. Fig. 2 is a sectional plan view taken on the line 2—2 of Fig. 1. Fig. 3 is an inverted plan view of Fig. 1. Figs. 4, 5 and 6 are respectively an elevation, a sectional elevation and a plan view of a chuck or like tool holder as constructed according to a slightly modified arrangement of our improvements. Figs. 7 and 8 embrace elevations and plan 35 views of details in the mechanism which will be hereinafter more particularly referred to. Figs. 9 and 10 are respectively an elevation and a sectional elevation at right angles to same of another slightly 40 modified construction of chuck. Fig. 11 is a sectional plan view with the driving spindle removed and taken on the line 11—11 of Fig. 10. Fig. 12 is a plan view of a detail in the mechanism which will also 45 be hereinafter more particularly referred to. Fig. 13 is a sectional elevation of the chuck, while Figs. 14 to 17 are views of details of the construction which will also be herein- 50 after more particularly referred to.

Referring to these drawings, the paws or 55 wedges *a*, which are cylindrical or round in cross section and tapered at their lower ends, are formed with recesses *b* and inwardly projecting flanges *c* at their upper ends.

These paws are fitted into recesses *d* formed

in the internal surface of the partly conical cylindrical sleeve *e* and a small ball *f* placed into a recess in each paw and working in a groove *g* in the recess *d* keeps said paw in its proper position, that is, it prevents the paw from twisting or turning about its own longitudinal center line or axis. 60

A plug *h* screwed into the upper portion of the sleeve *e* is bored for the passage of the driving spindle *i* and is fitted at its lower or inner end with a screwed stud or plug *j* formed with a notch, groove or channel *k* at its upper end or face to receive the end of the spindle which is shaped to fit same. The lower end of the stud *j* is provided with a head or circular flange *l* formed with a notch, groove or channel *m* to receive the upper end of the tool shank *n* which is correspondingly shaped and this 70 head fits into the recesses *b* of the paws *a* whose flanges *c* bear on its upper surface. 75

A pinching screw *q* is preferably fitted into the plug *h* in order that the spindle *i* may be tightened in the plug *h*. 80

It will be readily understood that as the spindle *i* is rotated the tool *n* is positively rotated from same through the stud *j* by means of the projections or shaped portions on the ends of the spindle and tool shank 85 engaging with the grooves or channels *k*, *m*, in the stud *j* and as the sleeve *e* is rotated on the plug *h* to tighten the paws *a* on the tool shank *n* the flanges *c* of the paws bearing on the head *l* of the stud *j* will prevent 90 the paws from being forced longitudinally along the tool shank so that said paws will only have a movement in a direction at right angles to the longitudinal axis of the tool shank. 95

If desired, balls *o*, *p*, may be fitted between the flanges *c* and the plugs *h* and *j* in order that friction may be minimized. 100

As illustrated by Figs. 4 to 8, a sleeve 1 (hereinafter termed the inner sleeve) is mounted on the lower or outer end *s* of the driving spindle *i* preferably between collars *t* and *u*, so that the same has practically no longitudinal movement on said spindle although it is capable of a rotary movement on same. The lower end *s* of the driving spindle *i* engages with and drives the tool holding means or device proper *h*, the upper portion *v* of which is preferably of a sleeve or socket formation which embraces or encir- 105 110

cles said spindle end *s* and which is formed at its upper end with teeth or notches *w* which engage with a pin *x* passed through the spindle end *s* so that when the pin *x* is in engagement with the notches *w* of the tool holder *h* and the spindle *i* rotated, the tool holder *h* will be rotated also.

In order that the pin *x* will be disengaged from the said notches *w* so that the tool *n* will not be revolved as the spindle *i* revolves, a pin or projection *y* secured near to the upper end of the tool holder socket *v* works in an inclined slot *z* formed in the said inner sleeve 1 so that if the spindle end *s* and tool holder proper *h* are in engagement (by means of said pin *x* and notches *w*) are being revolved and the inner sleeve 1 is held by the operator the slot *z* in the sleeve 1 travels over the pin *y* in the socket *v* and 20 raises the pin *x* in the spindle end *s* out of engagement with the notches *w* of the socket *v* so that the tool holder proper *h* is disconnected from the spindle end *s*.

A sleeve 2 (hereinafter termed the outer sleeve) mounted around the inner sleeve 1 is of a tight fit to same so as to form a grip for the operator when he desires to hold the inner sleeve 1; and if desired, these sleeves 1 and 2 may be held from rotating by automatic means instead of by the operator manually. This automatic means may consist of a downwardly projecting member or members 3 secured to the outer sleeve 2 and preferably adjustable as regards length, which 35 comes into contact with the surface 4 of the work when the drill or other tool *n* has reached the desired depth, thus preventing the sleeve 2 from being rotated and so disengaging the tool holder *h* from the driving 40 spindle *i* as hereinbefore described. These downwardly projecting members 3 may be adjustable as regards length by any suitable means, for example, their upper ends may be secured to a spring collar 5 or like device adjustable as regards its position on the outer sleeve 2, or both arrangements may be used if desired.

The aforesaid pin *x* on the driving spindle end *s* and the notches *w* on the socket *v* of tool holder *h* may be used in conjunction with the driving plug *j* between the spindle end *s* and the tool shank *n* illustrated by and described in connection with Figs. 1 to 3.

In the modification illustrated by Figs. 9 to 12 two pins *y* each engaging with an inclined slot *z* formed in the sleeve 1 are used instead of the one pin *y* and slot *z* illustrated by Figs. 4 to 8, while the teeth or notches *w* and the pin *x* are dispensed with. 60 A notch 6 is also preferably formed at the end of each slot *z* so as to permit the tool holder *h* to fall and be completely disengaged from the spindle end *s*. The outer sleeve 2 is also dispensed with and a milled or roughened surface 7 to form a grip for

the operator is formed on the upper part of the sleeve 1.

A washer 8 is preferably fitted into the lower end of the socket *v* and the driving plug *j* is secured into same, while the tongue *h* at the spindle end *s* engages with a groove 9 formed in the upper end of the plug *j* and washer 8.

The paws or wedges *a*, are cylindrical or circular in cross section and are formed at their one end with flattened portions 10 in which notches 11 are cut so that heads 12 (which correspond to the heads *c* of Fig. 1) are formed.

The notches or necks 11 of the paws *a* 80 loosely fit slots 13 formed in a disk or plate 14 mounted on the stud or plug *j* screwed into the head *h* of the shank, spindle or socket *v* of chuck. The cylindrical and partly conical sleeve *e* which screws on head 85 *h* of shank *v* is formed with holes or orifices (one for each paw) in its conical part so that when the sleeve *e* is screwed on to head *h* the paws *a* are forced toward the longitudinal center line of the tool shank 90 *n*. The plug *j* is formed with a head *l* between which and the head *h* the plate 14 is mounted so that when the paws *a* are tightened on the tool shank *n* the head 12 bearing on the plate 14 which in turn bears 95 on the head *l*, prevents said paws from having any movement along the tool shank *n*. A washer or disk 15 is preferably fitted between the heads 12 of paws *a* and the head *h* of spindle *v*. The head *l* of plug *j* is 100 formed with a slit or groove *m* into which the tongue or projection 16 formed at the upper end of tool shank *n* is fitted so that positive means are provided for preventing the tool from having any rotary motion independent of the plug *j*. The other end of plug *j*, that is the screwed end, is also formed with a groove 9 into which the tongue *h* formed at the end *s* of a spindle *i* passing 105 through the shank *v* is fitted. When the tool is to be rotated, such as in a boring and drilling machine, the spindle *i* is driven in any suitable manner and the grooves *m* and 110 9 and the tongues 16 and *h* insure that the tool *n* is positively rotated from the said spindle *i*. When the tool is not to be rotated, such as in a lathe where the work rotates, the spindle *i* being held rigid, the said 115 grooves and tongues *m*, 9, 16 and *h* insure that the tool is also held rigid.

A cover or disk 17 is preferably fitted around the spindle *v* and screws into the sleeve *e*.

The necks 11 of the paws *a* are loosely fitted into the slots 13, as before mentioned, 125 and since said paws are circular in cross section and are fitted into similarly shaped holes in the sleeve *e* when said sleeve is screwed on the head *h*, to tighten the paws 130 on the tool shank, said paws will be rotated

for a small part of a revolution about their own longitudinal center line, the play or looseness between the necks 11 and the sides of the slots 13 regulating the amount of this movement. The other end of each paw *a* that is the opposite end from the head end, is formed tapered (Figs. 13 and 15) that is, it has a knife edge 18 which is placed along the tool shank *n*. When the paws are tightened on to said shank, their aforesaid small rotary movement turns the edges 18 from off the tool shank and when the tool starts to drill on the work the pressure between the cutting edge of the tool and the work causes said tool to have a tendency to rotate in a direction opposite to the partial rotation of the paws so that a locking or jamming action or effect takes place between the knife edges of the paws and the tool shank.

What we claim is:—

1. The combination in a chuck of a conical outer sleeve, having recesses and grooves; paws fitting the recesses of said sleeve; and balls in the grooves of the sleeve engaging the paws.
2. The combination in a chuck of a sleeve; paws therein; a plug engaged by said sleeve; a spindle connected to the plug; a stud mounted in the plug and operatively connected to the paws; and a tool shank, there being plug and recess connections between the stud, the spindle and the tool shank.
3. The combination in a chuck of a spindle; a tool holder; a socket embracing said spindle end and connected to the tool holder; a pin fitted to said socket; and a sleeve surrounding the socket having slots for the reception with said pin.
4. The combination in a chuck of a driving spindle; a tool holder; a socket on said tool holder and embracing the lower end of the driving spindle; teeth at the upper end of said socket; with a pin fitted to the spindle end engaging said teeth.
5. The combination in a chuck of a driving spindle; a tool holder; pin and slot devices for disengaging the tool holder from the driving spindle; with means including a tooth and pin device for transmitting power from said driving spindle to the tool holder.
6. The combination in a chuck of an inner sleeve having a slot; an outer sleeve fitting said first sleeve; a tool holder; with a pin

secured to the tool holder and extending into said slot of the inner sleeve.

7. The combination in a chuck of a tool holder; a sleeve; a pin and slot connection between said sleeve and the holder; with means whereby said sleeve is automatically unclutched when a tool in the holder reaches the depth desired.

8. The combination in a chuck of a tool holder; a sleeve; a pin and slot connection between said parts; with a downwardly projecting member adjustable as regards length and secured to the sleeve, for automatically unclutching the same when a tool in the holder reaches the depth desired.

9. The combination in a chuck of a casting; a member therein having slots; paws having T-shaped heads and mounted with their necks in said slots to have a small rotary movement about their respective center lines as axes; and a tool shank to which said paws are gripped by reason of such rotary movement as caused by the action of the tool on the work.

10. The combination in a chuck of means including paws whereby a tool may be either positively rotated or positively held from rotation; and means permitting rotation of the paws about their respective center lines to cause them to grip the tool shank by reason of the action of the tool on the work, the same consisting of a radially slotted supporting plate slidably engaging the paws while allowing them limited rotation.

11. The combination in a chuck of a casting; a driving spindle; a stud connected to said spindle; a disk rotatably mounted on the stud and having slots; with paws or wedges formed with heads and neck parts mounted in said slots.

12. The combination in a chuck of a spindle having a head; a stud secured in said head; a disk rotatably mounted on said stud and paws engaged by the disk to prevent their movement longitudinally independently of the spindle.

In testimony whereof, we have signed our names to this specification, in the presence of two subscribing witnesses.
